JOHN NOBLIT, OF PHILADELPHIA, PENNSYLVANIA.

Letters Patent No. 73,920, dated January 28, 1868.

IMPROVEMENT IN HAIR-CLOTH.

The Schedule referred to in these Letters Patent and making part of the same.

TO ALL WHOM IT MAY CONCERN:

Be it known that I, JOHN NOBLIT, of the city and county of Philadelphia, State of Pennsylvania, have invented a new and improved Hair-Cloth; and I do hereby declare that the following is a full, clear, and exact description thereof, reference being had to the accompanying drawings, making a part of this specification, in which—

Figure 1 is a front sectional elevation of certain parts of a loom, which latter is adapted for weaving my improved hair-cloth.

Figure 2 is a top view of fig. 1.

Figures 3, 4, and 5 show the three different positions of the hair-nippers in distributing the hairs in the shed.

Figure 6 is a top view of the hair-nippers and race-beam.

Figure 7 shows the arrangement of the hairs in the warp-threads.

Similar letters of reference indicate corresponding parts in the several figures.

This invention relates particularly to an improvement on the manufacture of a fabric which is known as hair-cloth, it being composed of hairs and threads woven together, so as to present a surface which is entirely of hair. Under all the modes hitherto adopted of weaving this fabric there is a great waste of hair, in consequence of such modes involving the necessity of having the hairs equal in length to the width of the cloth which it is desired to weave, for which reason wide and very wide hair-cloth is very expensive.

The object of my invention is to provide for utilizing short hairs in the manufacture of hair-cloth, by interweaving these hairs with the warp in such manner that a given width of cloth can be made of hairs which are very little longer than half the width of such cloth; or, if desirable, cloth can be made which is nearly double the width of any cloth hitherto made of a given length of hairs, as will be hereinafter described.

To enable others skilled in the art to understand my invention, I will describe its construction and operation.

In the accompanying drawings, I have represented certain parts of a loom which is adapted for weaving my improved hair-cloth; and, while I prefer to employ such parts, I do not confine my invention to their use. The main part of the loom which I have represented is constructed after the plan described by me in my Letters Patent dated on the ninth day of April, 1861.

A represents the main frame of the loom, and B is the vibrating lay-frame, carrying the nippers which distribute the hairs in the shed. This frame, B, receives its motions from a rotating crank-shaft, C, extending transversely across the top rails of frame A, and receiving motion from any suitable prime-mover. The shaft C has three cranks upon it, two of which are connected to the frame B by means of pitman-rods, D D, while the other communicates motion to the rock-shaft E through the medium of a pitman-rod, F.

To the forward part of the rock-shaft E an arm, G, is pivoted, in such manner as will allow this arm to vibrate in a direction with the length of said shaft, at the same time that it receives a lateral vibration, in consequence of the oscillation of said shaft. The upper end of the arm G is forked for receiving the lower edge of the arc α of the lay-frame, which latter guides said arm in its lateral as well as longitudinal vibrations. To the upper end of the arm G one end of a pitman-rod, H, is pivoted, the opposite end of which is pivoted to an arm which is formed on the rear end of a nipper-box, I, and which passes through a long slot made through the race-beam of the lay-frame B, as shown in fig. 1.

Other parts of the loom may be constructed in the usual well-known manner, with the following exceptions: The nipper-box I carries two nippers, b and c, one of which, b, is longer than the other, as shown in the drawings. These nippers are long, narrow pieces of metal, pivoted within a channel formed in the box I by means of a transverse pin at e, and acted upon at their rear or outer ends by means of springs, which keep their gripping-ends down upon the jaw f of the box I. The rear upper edges of the nippers b c have elevations or cams formed on them, which are acted upon at certain times by dogs or pivoted cams, which latter raise the gripping-jaws of said nippers.

The dogs g g are pivoted to the upper ends of two standards, h h, rising from the race-beam; and these dogs are so arranged that they raise or open the jaws of the nippers at proper times for receiving the hairs. The dog g¹ is pivoted to a standard, h¹, and so arranged as to open the nipper-jaw b at the proper time to drop

one of the hairs; and the dog g^2 ; which is pivoted to the standard h^2 , is so arranged as to raise the jaw e at the proper time to drop the other one of the hairs.

The tufts of hairs are suitably attached to one end of the race-beam, opposite the small metal catches i and i' . The points or smallest ends of the hairs of the tuft which is opposite the catch i are upward, and the butts or largest ends of the hairs of the tuft which is opposite the catch i' are upward. The catches i and i' are secured upon a strip, j , the upper surface of which is in the plane of the lower griping-jaw f ; and these catches are arranged at proper distance apart to deliver the hairs between the griping-surfaces of the nippers, when in the positions shown in fig. 3.

In order that the hairs shall be taken by the nippers, a person is stationed at one end of the loom, who draws out the hairs one at a time, and fastens the ends under the catches i and i' , so that, at every backward stroke of the nippers, two hairs are carried into the shed, and beaten up by the lay. When the nippers have moved an inch or more past the middle of the width of the shed, the dog g^1 raises the nipper-jaw b , and releases one of the two hairs; and, when the nippers have moved such a distance as to bring the other hair in the proper position, the dog g^2 raises jaw e , and drops this hair. While the nippers are delivering the hairs between the warp-threads or shed, the person stationed at one end of the loom adjusts two hairs in proper position to be gripped by the nippers on their return. By these means the woven fabric will present the appearance indicated in the diagram, fig. 7; that is to say, the inner ends of every lay of hairs will overlap or extend past each other an inch or more.

In order to have the fabric present an even appearance and level surface, the hairs are drawn from the tufts by "butts" and points, and the points of the hairs left in the middle of the fabric.

In consequence of the peculiar movements given to the harnesses of hair-cloth looms for presenting a compact hair-surface upon one side of the cloth, the hair will be crimped and interwoven with the warp-threads, in such manner as to leave that portion of the cloth where the hairs overlap as strong as if not stronger than any other part of the fabric.

As above described, the loom is adapted for weaving only one width of cloth. To adapt it for weaving different widths, I make oblong slots, ll , through the race-beam, through which the bolts pass that secure the two standards h^1 and h^2 to said beam. These slots admit of the adjustment of the standards h^1 and h^2 with their pivoted dogs, so that hairs of different lengths can be dropped at different times.

It will be seen, from the above description, that I produce a new and improved fabric, composed of hairs, the ends of which overlap each other in the middle of its width, as indicated in fig. 7. It will also be seen that this fabric is nearly double the width of the length of hairs composing the woof.

While I am enabled to make hair-cloth nearly double the width of hair-cloth hitherto made, this is not so much the object of my invention as it is to utilize hairs, which, under the old modes of weaving, are too short for salable cloth.

If desirable, more than two nippers or hair-carriers may be employed, and arranged so as to drop three or more hairs in the shed at every backward stroke, in which case the throw of the nippers or hair-carriers would have to be increased, and an additional number of lifting-dogs arranged at proper points upon the race-beam.

Having described my invention, what I claim as new, and desire to secure by Letters Patent, is—

1. Two or more nippers or hair-carriers in a loom for weaving hair-cloth, which are operated so as to close upon two or more hairs simultaneously, and then to drop the hairs singly and at different points in the shed or warp, substantially as described.

2. A fabric, each lay of the woof of which is composed of two or more hairs laid together, substantially as described.

JOHN NOBLIT.
